(57) **CLAIM**

The ornamental design for a bottle, as shown and described.

DESCRIPTION

FIG. 1 is a front, right, and top perspective view of an opaque embodiment of a bottle showing the new design;

FIG. 2 is a front view thereof;

FIG. 3 is a rear view thereof;

FIG. 4 is left side view thereof;

FIG. 5 is a right side view thereof;

FIG. 6 is a top view thereof;

FIG. 7 is a bottom view thereof;

FIG. 8 is a front, right, and top perspective view of a transparent embodiment of the bottle;

FIG. 9 is a front view thereof;

FIG. 10 is a rear view thereof;

FIG. 11 is left side view thereof;

FIG. 12 is a right side view thereof;

FIG. 13 is a top view thereof; and,

FIG. 14 is a bottom view thereof.

The broken lines shown in FIGS. 1-14 illustrate portions of the bottle that form no part of the claimed design.
